UNITED STATES PATENT OFFICE.

WARREN E. WILLIS, OF NORTH ATTLEBORO, MASSACHUSETTS, ASSIGNOR TO E. L. FRANKLIN & CO., OF NORTH ATTLEBORO, MASSACHUSETTS, A CO-ARTNERSHIP CONSISTING OF WALLACE G. FRANKLIN, CLARENCE W. FISHER, AND ELTON B. FISHER.

LOCKET.

1,412,765.

Specification of Letters Patent. Patented Apr. 11, 1922.

Application filed July 20, 1921. Serial No. 486,060.

To all whom it may concern:

Be it known that I, WARREN E. WILLIS, a citizen of the United States, residing at North Attleboro, in the county of Bristol 5 and State of Massachusetts, have invented certain new and useful Improvements in Lockets, of which the following is a specification.

My invention has relation to lockets, in 10 which may be safely enclosed and carried pictures, mementos and the like and consists in an improved method of constructing a locket and in the improved locket produced thereby.

15 My improved locket is made up of four parts, namely, a rim, back and front members, preferably of concavo-convex form, in order to form a shallow chamber between the two parts, when assembled, and a lock- 20 link member.

In the drawings:

Figure 1 is a front plan view of the locket;

Figure 2 is an edge view of Figure 1;

25 Figure 3 is a view of the rim;

Figure 4 is a view of the link member in perspective;

Figure 5 is a view of rim wire spirally wound upon a mandrel or former, with 30 some of the studs affixed;

Figure 6 is a cross-section of the locket on line 6—6 of Figure 1.

The object of my invention is to produce a locket, tight, cheaply made and assembled, easily opened and closed, and of neat 35 appearance.

To this end I form a rim of wire, drawn to a concavo-convex shape in cross-section, as shown in Figure 6, the hollow or concave face being the inner side of the rim, 40 in use, and the convex face being the outer side of the rim in use. A suitable length of this wire is spirally wound, side by side, upon a mandrel or forming shaft, preferably of cylindrical shape, as shown in Figure 5, the inner hollow side, *a*, being next the mandrel *M*. A line, *m*, parallel with the axis of the mandrel, is drawn across the coils of wire, and on each coil at an 45 equal distance from the line *m*, on either side of the line *m*, are affixed studs, *S*. Several of these pairs of studs are shown as affixed, in Figure 5, and such studs will be affixed to every coil of the spiral and the

spiral is then cut along the line *m*, the result 55 being a multiplicity of split rings, *R*, as shown in Figure 3, forming the rim, *R*. Or the spiral may be cut before the attachment of the studs *S*, and the studs *S* attached to the rings, separately. 60

The inner diameter of these rings, *R*, will be determined by the size of the mandrel, *M*, in accordance with the desired size of the finished locket, and it may be noted that the front and back concavo-convex members, 65 *F*, may be suitably formed of crystals such as are used upon watches, and, as these are of various standard sizes, the rims *R* may be formed to receive any of the standard sizes desired, or sizes specially made, or 70 the parts *F* may be one or both formed of other material than glass and of any desired size.

The lock-link *L* is formed of resilient material, preferably metal, curved, as shown in 75 Figure 4, and having apertures, *1*, at each end, and carrying at its centre a spring loop which serves also as an attaching means for the chain in use. On the edges of the arms of the lock-link are formed depending 80 flanges or skirts, *2*. It will be noted that the studs *S* are set at unequal distances from the split in the ring, and that when the locket is assembled the split comes beneath the flange *2* and the ends are thus 85 forced into and held in perfect alignment and the joint hidden. This function of the flanges is of importance, since the rings are originally formed as a spiral, are then cut into rings, but retain their spiral form 90 until the ends are forced into alignment, and the ends have a tendency to return to the spiral if uncontrolled.

The locket is assembled by bringing the edges of a pair of front and back members *F* together, the convex surface of the members being outwardly disposed, slipping the edges of the members *F* within the hollow, *a*, of rim *R*, pressing the ends of the rim into butted relationship, placing one aperture 1 of link *L* over one stud *S* and the other end of the link upon the other stud and pressing the link at the center to partially straighten and lengthen the link until the other aperture 1 slips over the other 105 stud *S*. Upon releasing pressure on the link, the resiliency of the link will cause it to try to regain its original "set" or curve

and will tend to draw the studs S toward one another, thus holding all the parts together, until released by prying up one end of the link from one of the studs S, when 5 the parts may be disassembled.

I claim:

1. The locket above described, made up of a front and a back member; a rim, formed as a split ring, surrounding and engaging 10 the edges of the front and back members; a pair of studs, spaced apart and each fast on the split ring on opposite sides of the split; a spring link engaging both studs and drawing the rim and holding the rim 15 and front and back members in fixed relationship.

2. The locket above described, made up of a front and a back member; a rim, formed as a split ring, surrounding and engaging the edges of the front and back members 20 and carrying on opposite sides of the split and at unequal distances therefrom, a pair of studs; a link formed with a spring loop midway of its length and having depending flanges on both sides of each arm of the 25 link, the link engaging both studs and the flanges holding the ends of the split ring in perfect alignment.

Signed at North Attleboro, Massachusetts, this 18th day of July, 1921.

WARREN E. WILLIS.
